UNITED STATES PATENT OFFICE

JOHN RALPH FEHR, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed December 2, 1926. Serial No. 152,263.

This invention relates to cooling units for mechanical refrigerators, and more particularly to cooling units which are adapted to be installed in refrigerating cabinets of the 5 household type. However, it is to be understood that the present invention may be adapted for larger refrigerating cabinets of the commercial type.

The present invention includes among its 10 objects the provision of a cooling unit of simple and economical construction which will quickly congeal or freeze substances which are placed within a freezing compartment provided by the unit, and which will effectively cool the food compartment of the cabinet.

Further objects and advantages of the present invention will be apparent from the following description, reference being had to 20 the accompanying drawings, wherein a preferred form of the present invention is clearly shown.

In the drawings:

Fig. 1 is a front view of a refrigerator cabinet with the doors open in order to show the food compartment and a cooling unit within a cooling compartment;

Fig. 2 is a view on a larger scale than Fig. 1, showing the front view of the cooling unit 30 which is suspended within the cooling compartment of a cabinet, the walls of which are shown in vertical section; and

Fig. 3 is a side elevation of the cooling unit drawn to the same scale as Fig. 2.

Referring to the drawings, 20 designates a refrigerator cabinet which provides an L-shaped food compartment 21 separated from a cooling compartment 22 by a horizontal 40 partition 23 and a vertical partition 24. The partition 24 is provided with a flue 25, admitting relatively warm air from the food compartment 21 to the cooling compartment 22; and the partition 23 is provided with a flue 26, admitting cooled air from the compartment 22 to the compartment 21. The partition 23 supports a baffle 27 which prevents moisture, dripping from the cooling unit above, from entering the flue 26. The baffle 27 directs such 50 moisture upon the upper surface of the par-

tition 23, and this moisture is conducted away through a drain pipe 28.

The cooling unit located within the cooling compartment 22, includes a boiler or header 30 attached to the top wall of the cabinet by 55 bracket members 31 and 32. Condensed refrigerant is conducted to the header 30 from a compressor and condenser (not shown) through a pipe 33 and a fitting 34. Refrigerant is admitted from the fitting 34, as 60 needed, by a float-controlled valve (not shown), of suitable construction, located within the header 30. Expanded refrigerant is conducted back to the compressor through a fitting 35 and a pipe 36. The refrigerating 65 compressor and condenser with which the pipes 33 and 36 are connected, may be located outside of the cabinet, if desired, or may be placed within a machine compartment located below the food compartment 21, said compartment having a removable front wall 37 provided with louvres 38.

The cooling unit includes also a plurality of ducts 40 and 41 connected at their upper ends to the header 30 and, at their lower ends, 75 to a second header or manifold 42 arranged preferably vertically below the header 30. These ducts are arranged in horizontal rows, the rows of ducts 40 being in staggered relation to the rows of ducts 41 so that the outer 80 ducts 40 will not overlie the inner ducts 41 and obstruct the free circulation of air into contact with the inner ducts 41 as the cooled air descends between the ducts 40. The staggered relation of ducts also permits frost to accumulate to a greater degree upon the ducts 41 before air circulation adjacent the outer ducts 40 is obstructed, than is possible if the rows of ducts were not in staggered relation. Also, 85 the holes in the header for receiving the ends 90 of the ducts may be staggered, so as to permit close spacing of these holes without unduly weakening the walls of the headers.

The headers 30 and 42 and the ducts 41 co-operate to enclose a quick-freezing space or zone 43 within which metal trays 44 containing substances to be frozen may be placed within metal shelves or sleeves 45 attached to the ducts 41 and thermally connected therewith by brazing, soldering or the like.

In operation, the space 43 becomes much colder than other portions of the cooling chamber 22 because it is somewhat isolated from the warmer currents of air circulating about the cooling unit due to the isolating walls provided by the ducts and headers, and, due also to a wall of frost which will accumulate to a greater degree upon the ducts 41 and header 42 than upon the ducts 40 which are exposed entirely to air currents. If desired, the ducts 40 may be provided with outwardly extending vertical fins to increase the cooling action thereof upon the air passing thereover, and the ducts 40 and fins may be so proportioned as to de-frost to some extent during the idle periods of the refrigerating machine or even to remain partially de-frosted during operation of the machine, thereby further increasing the cooling effect thereof due to the absence of frost which tends to retard the transfer of heat from the air to the cooling unit.

By using the lower header 42 a rigid structure can be made, and the ducts may be made from short lengths of pipe, which might otherwise be discarded, while yet providing for free circulation of the refrigerant from and toward the upper header. The lower header serves also as a support upon which a substantial quantity of frost may accumulate further to isolate the freezing space 43.

While the form of embodiment of the present invention as herein disclosed, constitutes a preferred form, it is to be understood that other forms might be adopted, all coming within the scope of the claims which follow.

What is claimed is as follows:

1. A cooling unit for mechanical refrigeration comprising: a plurality of elongated headers one above the other, and a plurality of ducts connecting the headers, certain ducts cooperating with the headers to enclose a freezing space, and certain other ducts being located so as to be exposed substantially entirely to air circulating adjacent the cooling unit.

2. A cooling unit according to claim 1, in which the ducts which are adjacent the freezing space are arranged in at least two vertical rows on either side of the space between the headers.

3. A cooling unit according to claim 1, in which the ducts are arranged in spaced, vertical rows, the inner rows cooperating with the headers to enclose a freezing space, and the other rows located so as to be substantially entirely exposed to air circulating adjacent the cooling unit.

4. A cooling unit according to claim 1, in which ice-tray shelves are supported by the ducts immediately adjacent the freezing space.

5. A cooling unit for mechanical refrigeration comprising, a plurality of headers and a plurality of ducts connecting the headers,

certain ducts connected between two of said headers being spaced apart to enclose therebetween a freezing space and certain other ducts being located spaced from said freezing space.

6. A cooling unit for mechanical refrigeration comprising, a plurality of headers and a plurality of ducts connecting the headers, certain ducts connected between two of said headers being spaced apart to enclose therebetween a freezing space and certain other ducts being located spaced from said freezing space, and ice-tray supports supported in said freezing space.

7. A cooling unit for mechanical refrigeration comprising two headers, opposed duct means each connected with both of said headers and cooperating to provide a freezing zone therebetween, and duct means lying outwardly of the freezing zone and connected with one of said headers.

8. A cooling unit for mechanical refrigeration comprising two headers, opposed duct means connected with one of said headers and cooperating to provide a freezing zone therebetween, and opposed duct means lying outwardly of the freezing zone and connected with both of said headers.

9. A cooling unit for mechanical refrigeration comprising two headers, duct means connected with one of said headers, duct means opposed to the first duct means and connected with both of said headers and cooperating with the first duct means to provide a freezing zone and duct means connected with both of said headers and lying outwardly of the first duct means.

10. A cooling unit for mechanical refrigeration comprising two headers, duct means connected with one of said headers, duct means opposed to the first duct means and connected with both of said headers and cooperating with the first duct means to provide a freezing zone, duct means connected with one of said headers and lying outwardly of the second duct means, and duct means connected with both of said headers and lying outwardly of the first duct means.

11. A cooling unit for mechanical refrigeration comprising two headers, duct means connected with one of said headers, duct means opposed to the first duct means and connected with both of said headers and cooperating with the first duct means to provide a freezing zone, opposed duct means connected with both of said headers and lying outwardly of the freezing zone.

In testimony whereof I hereto affix my signature.

JOHN RALPH FEHR.
